AUTOMATIC FLATIRON

Edward A. Roehl, Frank W. Carpenter, and Maurice L. Warner, Minneapolis, Minn., assignees to Dominion Electrical Mfg. Co., Minneapolis, Minn., a corporation of Minnesota.

Application October 15, 1932, Serial No. 637,936

1 Claim. (Cl. 219—25)

Our invention relates to electrical heating appliances and particularly to automatic electric flatirons.

It is an object of our invention to provide, in an electrically heated flatiron, a novel, very sensitive, and inexpensive means for automatically maintaining the sole plate of the flatiron at a substantially constant predetermined temperature.

Another object is to provide temperature regulating means of the class described which may be easily and rapidly adjusted to maintain various temperatures and wherein the temperature of the sole plate is the index by which the action of the regulating means is governed.

Still another object is to provide an electrically heated flat iron wherein the sole plate is constructed of material having a relatively high thermal coefficient of expansion, and wherein the relative movement afforded by unequal expansion and contraction of said sole plate and a member constructed of material having a relatively low thermal coefficient of expansion is utilized for actuating electrical contacts connected in the circuit of the heating element of the flat iron.

These and other objects and advantages of the invention will be more fully set forth in the following description made in connection with the accompanying drawings, in which like reference characters refer to similar parts throughout the several views, and in which:—

Fig. 1 is a side view of our flat iron;

Fig. 2 is a top view with the handle, casing, and pressure plate removed;

Fig. 3 is a vertical cross sectional view taken along the line 3—3 of Fig. 2 as indicated by the arrows;

Fig. 4 is a longitudinal vertical sectional view taken along the line 4—4 of Fig. 2 as indicated by the arrows;

Fig. 5 is a top view of another form of our invention with the handle, casing, and pressure plate removed;

Fig. 6 is a longitudinal vertical sectional view taken along the line 6—6 of Fig. 5 as indicated by the arrows, and

Fig. 7 is an enlarged, vertical sectional detailed view of the insulated connecting element between the lower contact arm and the actuating lever therebelow.

Referring to the drawings, and particularly to Figs. 1, 2, 3 and 4, a sole plate 10 is of conventional shape, but is constructed of aluminum or other metal having a relatively high thermal co-

efficient of expansion. Above the sole plate 10 is an electrical heating element 11 of conventional form enclosed by an insulating and heat conducting casing 12, formed of mica or other heat resistant electrical insulating material. From 5 slightly forward of the middle thereof to the rear end thereof the mica casing 12 has a portion cut away along and adjacent its longitudinal center line to leave a V-shaped opening 12b as shown in Fig. 2. Above the mica casing 12 is a pressure 10 plate 13, the lower side of which is recessed above the cut away portion of the mica casing 12 as best shown in Figs. 3 and 4. Screws 14, passing through apertures in the pressure plate 13, through apertures 12a in the mica casing 12, and 15 into internally screw threaded apertures in the sole plate 10, pull the pressure plate 13 toward the sole plate 10 to firmly clamp the heating element 11 and its mica casing 12 between the pressure plate 12 and the sole plate 10.

Each of two flat resilient metal arms 15 and 16, disposed one above the other, parallel to each other, and in general parallel to the sole plate 10, carries at its outer end, one of a pair of co-acting electrical contacts 15a and 16a. The contact carrying arms 15 and 16 are disposed above and are longitudinally aligned with the V-shaped opening 12b in the mica casing 12 with their inner ends toward the rear. The inner or rear ends of the arms 15 and 16 are secured to the sole plate 10 by means of screws 17, insulating spacers 18 being interposed between, above, and below the arms 15 and 16, and the screws 17 being provided with insulating sleeves (not shown) and extending through aligned apertures in the arms 15 and 16 and the spacers 18 in a well known manner. The rearmost portion of each of the arms 15 and 16 extends a short distance beyond the rear edges of the spacers 18 to form terminals 15b and 16b.

A strip 19, formed of invar steel or other suitable metal either having a relatively low thermal coefficient of expansion or a zero thermal coefficient of expansion, is clamped at its rearward end between the lowermost one of the spacers 18 and the sole plate 10 and extends forwardly to a point near the forward end of the sole plate 10 whereat it is secured to the sole plate 10 by means of a screw 20 engaged in a suitable screw threaded aperture in the sole plate. The portion of the strip 19 lying beneath the medial and outer portions of the contact carrying arms 15 and 16 is arched upwardly and carries on its uppermost portion an upwardly projecting insulating button 21, the upper side of which is in contact with the 55

lowermost contact carrying arm 16. The arm 16 is so bent that it continually urges itself toward the button 21 so as to maintain contact therewith.

- 5 The contact carrying arms 15 and 16 are housed in the recessed lower side of the pressure plate 13 and a portion of the pressure plate 13 extends horizontally thereabove. Above and aligned with the outer portion of the uppermost 10 contact carrying arm 15, a vertically disposed screw threaded adjustment member 22 is engaged in a screw threaded aperture in the pressure plate 13 above which it extends a short distance. An insulating pin 23 is retained at its upper end 15 in a recess in the lower end of the adjustment member 22 and at its lower end bears upon the contact carrying arm 15. The contact arm 15 is so bent that it urges itself upwardly to maintain contact with the pin 23. The upper end of the 20 adjustment is of a square or other suitable shape. An adjustment lever 24 has a downwardly extending hub 24a in the lower end of which is a recess shaped to fit and engage with the upper end of the adjustment member 22.
- 25 A casing or shell 25 and handle supports 26, all of conventional form, are secured to the previously described structure in a well known manner by means of screws 27 passing through apertures therein and engaged with screw threaded apertures in the upper side of the pressure plate 13, as shown in Fig. 4. A handle 28, of a conventional type, is secured at its respective ends to the upper portions of the handle supports 26. A pin 32 projecting radially outwardly from the hub 35 24a is situated to strike the casing 25 to prevent vertical displacement of the hub and lever.

40 Connection prongs 29 of conventional form are insulatedly mounted in the upper rear portion of the casing 25, as shown in Fig. 4. One of the prongs 29 is electrically connected to one terminal of the heating element 11, the remaining terminal of the heating element 11 is connected to the terminal 16b associated with the contact carrying arm 16, and the terminal 15b associated 45 with the remaining one of the prongs 29. From the above it is obvious that the heating element is connected to the prongs 29 with the contacts 15a and 16a connected in series therewith.

45 A guide 30, for an electrical connection plug, and a stand 31, both of conventional form, are secured to the rear portion of the casing 25, as shown in Fig. 1.

50 Preferably, a dial 32 and a pointer 24a are associated with the adjustment lever 24 to assist 55 in positioning the lever to obtain various desired temperatures.

Operation

50 When our flatiron is placed in operation, the prongs 29 are connected to a source of electrical energy by means of a plug equipped electrical cord of conventional form. When the iron is first connected and is cold, the pair of contacts 15a and 16a are closed, and, hence electrical current will flow from one of the prongs 29, through the heating element 11, through the closed pair of contacts 15a and 16a to the remaining one of the prongs 29, and heat produced in the heating element 11 by means of the electrical current will flow into the sole plate 10 and incidentally into other parts of the flatiron structure.

70 As the various parts become heated they will expand and the sole plate 10, since it has a relatively high thermal co-efficient of expansion, will 75 increase in length to a relatively great extent.

The flat strip 19, since it has a relatively low thermal co-efficient of expansion, will increase in length only very slightly and hence will be tensioned longitudinally by the relatively great expansion of the sole plate. The said tensioning of longitudinal pulling of strip 19 flattens the arched portion thereof. Flattening of the arched portion of the strip 19 draws the insulating button 21 downwardly to permit the contact 16a to move downwardly away from the contact 15a to open 10 the electrical circuit to the heating element 11 and hence prevent further increase in the temperature of the sole plate 10. As the temperature of the sole plate 10 decreases the sole plate will contract at a greater rate than the strip 19 and 15 hence will cause the strip to arch upwardly to again close the contacts 15a and 16b to again close the circuit to the heating element with the result that heat will again be delivered to the sole plate. The above cycle will be repeated as long 20 as the iron is connected to a source of electrical energy and the ratio between the lengths of time during which the circuit is closed and the lengths of time during which the circuit is open will vary in accordance with the rate of delivery of heat to 25 the material being ironed and the air surrounding the iron. It is obvious that the operation of the contacts is governed directly by the temperature of the sole plate and that the sole plate will be maintained at a substantially constant temperature, the variation in temperature being 30 between very narrow limits.

35 Swinging of the lever 24 to one side or the other will rotate the screw threaded adjustment member 22 and obviously cause the member 22, the insulating pin 23 and the upper contact arm 15 to move upwardly or downwardly according to the direction of movement of the lever 24. If the upper contact arm 15 is lowered, the flattening of the arched strip 19 and hence the expansion 40 of the sole plate 10 causing the flattening will proceed to an increased extent before the contacts will open and hence the temperature at which the sole plate 10 will be maintained will be increased. Conversely, raising the upper contact will lower the temperature. It obviously follows that the temperature to be maintained may be adjusted as desired by properly positioning the adjustment lever 24.

45 Another form of our invention, shown in Figs. 5, 6 and 7, includes a sole plate 40, a pressure plate 41, a casing 42, a heating element 43, and a mica casing 44 for the heating element, all connected together in the same manner as the corresponding parts of the first described form. The sole 50 plate 40 is formed of material having a relatively high thermal coefficient of expansion.

55 The mica casing 44 is similar to the mica casing 12 of the first described form and is provided with a U-shaped opening 44a similar to the opening 12a of the mica casing 12.

60 The sole plate 40 has a recess 45 in the upper side thereof disposed below the U-shaped opening 44a and a groove 46 extending some distance forwardly therefrom. In the bottom of the outer 65 end of the groove 46 there is an aperture 47 extending downwardly into the sole plate 40.

65 A substantially horizontal lever 48 has at its inner end portion an apertured ear 48a depending from each side thereof. A pin 49 extends through 70 the apertured portions of the ears 48a and through an apertured lug portion 50a of a member 50, the lug portion 50a being disposed between the ears 48a and the member 50 being secured to the bottom of the rear portion of the recess 45 in 75

the sole plate 40 by means of a screw 51. A short rod 52 having a diametrical aperture through the medial portion thereof is supported at its respective ends in aligned apertures in the upper portions of the ears 48a.

A relatively long thin rod 53 formed of material having a relatively low thermal coefficient of expansion has an angularly bent forward end portion disposed in the aperture 47 from which the 10 rod extends rearwardly in the groove 46 with its rearward end extending through the diametrical aperture in the short rod 52. The rear portion of the rod 53 is externally screw threaded and carries an internally screw threaded sleeve 54 the 15 forward end of which is in contact with the rearward side of the rod 52.

Above the lever 48 is a pair of thin flat forwardly extending arms 55 and 56 disposed one above the other and parallel to each other. The 20 arms 55 and 56 each carries one of a pair of coacting electrical contacts 55a and 56a. The rearward portions of the arms 55 and 56 have insulating spacers 57 above, below, and between them. Screws 58, provided with insulating sleeves, pass 25 downwardly through aligned apertures in a horizontally disposed web portion of a channel shaped supporting bracket 59, the spacers 57, and the arms 55 and 56, and are threadedly engaged in internally screw threaded apertures in a plate 60 located immediately below the lowermost one of the spaces 57. The screws 58 are drawn up snugly to clamp together the elements through which they extend. The depending flange portions of the channel shaped supporting bracket rest upon 30 the upper surface of the sole plate 40.

A flanged plug 61, formed of insulating material and having a metal loop 62 depending therefrom is carried in an aperture in the outer end portion of the lower contact carrying arm 56 as 40 shown in Figs. 6 and 7. The outer end of the lever 48 is of reduced width and extends through the loop 62.

An internally screw threaded bushing, disposed in an aperture in the pressure plate 41, is spot 45 welded or otherwise secured to the upper side of the web of the channel shaped supporting bracket 59 in alignment with an aperture therethrough located above the contact carrying arm 55. An externally screw threaded adjustment element 50 64, having a pin 65 formed of insulating material projecting from the lower end thereof, is threadedly engaged at its lower end in the bushing 63. The lower end of the insulating pin 65 bears upon the upper side of the upper contact carrying arm 55. The arm 55 is so bent that it urges itself upwardly against the insulating pin 65 to maintain 55 abutment therewith. An adjustment lever 66 has a depending hub portion 66a extending downwardly through an aperture in the casing. The 60 lower end of the hub 66a carries a member non-rotatively engaged in a non-circular recess in the upper end of the adjustment member 64. A pin 67, extending radially outwardly from the hub 66a prevents upward displacement of the lever 65 and the hub 66a.

Terminal prongs 68 similar to the prongs 29 of the first described form and similarly mounted are connected with the heating element 43 and the contact carrying arms 55 and 56 in the manner described in connection with the corresponding parts of the first described form.

In operation, as the temperature of the iron rises and the sole plate, since it is formed of metal having a relatively high thermal coefficient of ex-

pansion, increases its length to a relatively great extent and the rod 53, since it is formed of metal having a relatively low thermal coefficient of expansion, increases its length only very slightly. The result is that the rod 53 is pulled forwardly 5 to deflect the lever 48 downwardly and the lever 48 pulls the lower contact arm 56 away from the upper contact arm 55 to break the electrical circuit to the heating element and hence prevent further production of heat and increase in temperature. With the exception of the above, the operation of this form of our invention is identical with the operation of the first described form. 10

It is apparent that we have invented a novel, simple, rugged, inexpensive, and sensitive form 15 of electrically heated flat iron wherein means is provided for automatically maintaining the temperature of the sole plate within close limits, and wherein adjustment means is provided for adjusting the temperature at which the sole plate 20 will be maintained.

It will, of course, be understood that various changes may be made in the form, details, proportions and arrangement of the parts, without departing from the scope of my invention, which, 25 generally stated, consists in a device capable of carrying out the objects above set forth and in the novel parts and combinations of parts disclosed and defined in the appended claims.

Attention is called to the unusual sensitivity 30 of our heat controlling mechanism. Formerly, automatic flatirons and the like have had the thermostatic or sensitive element disposed deep in the interior of the device and usually surrounded by air. With the sole plate itself constituting the sensitive element, small changes of 35 temperature in the sole plate due to rapid transfer of heat cause the circuit through the heating element to be quickly closed. The actual part of the device which is impressed against the 40 clothes or articles heated is therefore the index of the temperature at which it is maintained. In actual tests with the iron up to temperature and the circuit through the heating element open, when the sole plate of the iron or even a small 45 portion, such as the tip thereof, is placed against a damp article of clothing, the circuit will be re-closed in less than 20 seconds.

What is claimed is:—

In a heating device, a heat transmissive plate 50 for applying heat to material to be treated, an electrical heating element associated with said plate for heating the same, said plate being constructed of material having a relatively high thermal co-efficient of expansion, an elongated 55 member of material having a relatively low thermal co-efficient of expansion, said member being secured at one of its ends to a point on said plate, a bell-crank having one relatively long arm disposed substantially parallel to said plate and a depending shorter arm swingably connected at its free end to a point on said plate widely spaced from said first point, the remaining end of said elongated member being connected to said bell-crank at the junction of 60 said arms, and an electric contact means electrically connected in the circuit of said heating element and having mechanical actuating connections with the free end of the longer arm of 65 said bell-crank whereby heating and cooling of said plate will respectively cause opening and closing of said contact means.
